UNITED STATES PATENT OFFICE.

ROSSITER S. SCOTT, OF NEW YORK, N. Y.

GARTER.

Application filed September 6, 1924. Serial No. 736,362.

This invention relates to garters and possesses several novel features as hereinafter explained. The general object is to improve the construction and efficiency of a garter and increase its comfort and utility. A specific object is to provide a garter which may be converted so that in one adjustment it will serve for holding up socks and in another adjustment it will be adaptable for holding up stockings such as golf stockings.

Another object is to afford a garter for socks which will be more flexible in application and operation, with free pivoting movements between all the parts of the garter, giving an improved self adjustment in conforming to the leg of the wearer and maximum comfort. Another object is to afford an improved mode of adjusting the circumference portion of the garter to the leg of the wearer. Other and further and more specific objects and advantages of the present improvement will be elucidated in the hereinafter following description of a convenient embodiment of the invention, or will be apparent to those skilled in the subject.

To the attainment of such objects and advantages the present invention consists in the novel garter and the novel features of arrangement, combination, construction, operation and detail as herein illustrated or described.

In the accompanying drawings Fig. 1 is a perspective view of a garter embodying the present invention, with the several parts mutually detached.

Fig. 2 is a view from the reverse side of one of the fastener members shown in Fig. 1.

Figs. 3 and 4 are plan and central section views of a modified form of fastener.

The drawings show the following elements. The band 10, which encircles the leg is preferably elastic. The strap 11 which extends from the band to the sock is preferably elastic. The lower end of the strap 11 may be arranged to have the usual clasp device for engaging a sock, including the clasp button 12 and the loop member 13.

The band 10, near its two ends, is provided with fastener members 14 and 17. The fastener member 14 may be a stud piece comprising a stud 15 consisting of a shank 15^b for receiving and pivoting strap 11 and an enlarged head at the top of the shank for attaching and pivoting the fastener

member 17 to the fastener member 14, and a base piece having bars 16 by which the fastener member can be sewed upon one end of the band 10.

The cooperating fastener member to stud 15 may be a socket piece 17 having a socket 18 of the type for example containing spring elements 19 so that it can be snapped upon the stud 15, and is so constructed in relation to stud 15 that when snapped upon the stud it can pivot thereon. The stud 15 is arranged to function as a dual pivot post for pivoting strap 11 and also the fastener member 17 and sufficient clearance or play is allowed between these various members to freely perform this function.

Preferably there is no adjustment of length of band to fit the circumference of the leg at any point between the two fastener members, but on the contrary the adjustment is effected at the fastener member or socket piece 17. This is shown as having slots at its opposite sides through which the elastic band 10 is passed first outwardly and then inwardly, leaving a projecting band end for maximum adjustment, which projecting piece may however be trimmed off after the requirement of maximum adjustment has been obtained. The slots 20 have deflected ends 21, thereby presenting metallic corners or points 22 which effectively grip the material of the band after the proper adjustment is made, and prevent slippage.

The converter strap 11 may be either detached, as indicated in Fig. 1, or connected to the fastener members at the ends of the band 10. For this purpose the upper end of the strap 11 is provided with a metallic coupling piece 23. This has a longitudinal slot 24 narrower than the head of the stud 15, but adapted to engage the shank 15^b of the stud, and to pivot freely thereon. The coupling piece 23 also has a cross slot 25 which receives the fabric at the upper end of the strap 11. The described slots are supplemented by an enlargement 26, which is at the interior side, concealed by the strap 11. This enlargement is opposite the end of the longitudinal slot 24. This arrangement allows displacement or depression of the fabric 11 into the enlargement area or recess 26 for the purpose of giving the area required to place the stud 15 into engagement with the slots. When the shank 15^b of the stud 15 has by this means been lo-

cated in the slot 24 the fabric resumes the position shown in Fig. 1 and by so doing prevents accidental detachment of the stud 15 from the slot 24. A manual pull between the members 23 and 12 may serve to stretch the fabric 11 and depress it into the recess 26, thus enabling the stud 15 to be slipped into the slots; or the stud 15 may simply be pressed against the fabric to displace it sufficiently to enable the shank 15^b of the stud 15 to slip into the slot 24. The fabric then acts as a guard against the stud 15 accidentally slipping out of the slot 24.

15 Many modifications of all parts of the device may be made within the spirit of the invention. As an instance Figs. 3 and 4 show a substitute stud member 14^a consisting of the stud part 15^a and an attaching rivet 16^a; which may be used in place of the corresponding parts 14, 15 and 16.

Used as a sock garter the coupling piece 23 of the strap 11 will be attached to the stud 15 as stated, and left there indefinitely. 25 The garter is readily applied by placing the band around the leg and snapping the socket member 17 to the stud 15. The three metallic pieces are thus all pivotally connected at one point, and all three parts are 30 freely swingable with relation to each other. The strap member 11 may assume any position and easily adapts itself to the contour of the leg, even though the sock clasp member might not be applied to the sock directly beneath the pivoting point, but on the angle. 35 The double swivel construction feature in this garter provides a very flexible adjustment to support socks of varying lengths. This advantageous structure gives a mutual 40 swivelling action between the two ends of the encircling band 10 and the top end of the strap 11; and the stud 15 is the common pivot or fulcrum connecting all three end members at one concentrated pivotal point 45 for flexibility.

Adjustment to the leg by the wearer is readily effected by shifting the band 10 through the slots of the socket member 17. The band should be picked out at the top 50 and loosened, pulled through to the desired extent and then tightened back into place. The usual metallic adjusting members part way around the band which are often irritatingly uncomfortable to the leg are thus 55 eliminated by combining the size adjustment with the 3-piece double pivoting connection.

When the wearer desires to use the garter for stockings, for example, when changing to golf costume it is only necessary to detach 60 the stud 15 from the coupling piece 23, by pressing down the stud piece 14 upon the fabric 11 which drives or depresses the fabric into the provided recess 26 and thus releasing the coupling piece 23 from the stud 65 piece 14. The detached band member 10 is

in condition to form a stocking band-garter encircling the leg, without the pendant or strap 11, the socket piece 17 being snapped upon the stud piece 14. The strap member 11 can be left attached to the sock until 70 ready to use the garter again as a sock garter.

It will thus be seen that I have described a garter embodying the principles and attaining the advantages of the present invention. Since various matters of construction, arrangement, combination and detail may be variously modified without departing from the principles involved it is not intended to limit the invention to such matters except in 80 so far as specified in the appended claims.

What is claimed is:—

1. A convertible garter comprising a band for encircling the leg, a connecting strap to extend between the band and the sock, and a connection between the band and strap, comprising a stud on one of said elements, and a coupling piece on the other having a slot for engaging the shank of the stud but too narrow to pass the head thereof, and an 85 enlargement of the slot formed in the coupling piece and covered by the fabric and into which enlargement a portion of the fabric may be temporarily deflected to permit the engagement of the stud with the slot. 90

2. A garter comprising a band, with stud and socket fastener members at its ends, and a strap with a slotted coupling member at its top, said coupling member having a narrow slot engageable with the stud shank, and a slot enlargement permitting the engagement of stud and slot, the parts arranged so that the material of the strap guards the slot enlargement against accidental detachment of the stud and coupling. 105

3. A garter comprising a band for encircling the leg having pivotal operating stud and socket fastening members at its ends, and a strap with a slotted coupling member at its top, said coupling member having a narrow slot pivotally engageable with the stud shank of the fastener member, and a slot enlargement permitting the engagement of stud and slot, the parts arranged so that the material of the strap effectively guards the slot enlargement against accidental detachment of the stud and coupling. 110

4. A convertible garter comprising a band to encircle the leg, with stud and 120 socket fastener members at its ends, a fabric strap to extend from such stud to the sock, said strap having a slotted coupling at its end, the slot thereof adapted to engage and disengage the stud of the band, and the fabric of the strap engaging the slot of the coupling. 125

In testimony whereof, I have affixed my signature hereto.
